UNITED STATES PATENT OFFICE.

HERBERT M. FRIENDLY, OF CHICAGO, ILLINOIS.

AUTOMATIC TELEPHONE SYSTEM.

Application filed August 22, 1924. Serial No. 733,460.

The present invention relates more particularly to automatic or machine switching telephone systems wherein lines are temporarily interconnected by remotely controlled switching mechanism.

The organization chosen to elucidate the invention comprehends a multi-office two-wire Strowger automatic or machine switching telephone system wherein five digits, or the equivalent, comprise the numbers of the respective called lines. It will be understood that the number of digits employed in directly establishing a connection between lines may be varied; five digits being taken for the exemplified system, as in general, commercial exchange operation this is the smallest number employed for multi-office systems. The invention is applicable to other types of line switching systems.

An object of the invention is to enable a switch, corresponding to a first numerical switch (as a so-called first selector in the exemplified system), to have direct access to one or more groups of outgoing inter-office trunk lines leading to respective remotely located ten-thousand groups or offices of the system as has been a well known practice. The respective said trunks of the group or groups terminate in so-called incoming second selectors. The said first selectors also have direct access to groups of local trunk lines; each latter said trunk line leading to a so-called local third selector (such as selector FS³ shown in the present application), located in the same office as the said first selector. That is, certain levels of the said first selector will contain respective groups of inter-office trunks leading to ten-thousand line groups of the exchange system numerically designated to correspond to the level position from which trunks lead from the first selector bank, and from other levels of the said first selector, groups of local trunks lead to so-called third selectors (having the second higher numerical order value with reference to the first selectors) in the same office as contains the first selector; all levels of bank contacts of the first selector being swept by the same set of wipers commonly.

Another object of the invention is to admit of employing all the levels of the first selector while at the same time precluding calls being vitiated by a so-called preliminary or false impulse or series of impulses which may be applied inadvertently before the directing dial is initially operated. Such false opera-

tion will be prevented from causing the call being progressed to a wrong called line, because the first selector will be thereby disabled against thereafter selecting until the 60 call is terminated. The bank levels of the first selector from which the inter-office trunks lead are chosen above the first or lowermost level. In the present exemplified system, the second level is the lowest level 65 used for inter-office trunks. However, it is preferred to have the third or a higher level as the lowest level used for inter-office trunks, as any possible initial false impulse or series constituting a first digit after initiating the 70 call by the removal of the receiver from the switch-hook, and before directly operating the dial, should be effective to disabling the call from being extended.

The larger the range of said false impulses 75 impossible of introducing an erroneous call the more effective the arrangement becomes. That is, if the second level is the lowest one used for inter-office trunks, and a false series of two impulses is accidentally introduced 80 by a careless movement of the switch-hook while removing the receiver, the wipers of the first selector will be caused to align with the second level and there rotate-in and select an inter-office trunk leading to an incoming second selector in the "2" ten-thousand group. Then, when the calling party directly annexes the five digits of the called line number, the first digit sent will be effective 85 to operate the incoming second selector of the "2" ten-thousand group, a number being reached responsive to the sending of the fourth digit which is not the one intended to be called; the fifth digit sent being idle so far as any linking operation is concerned. This 90 false impulsion sometimes manifests itself when a line becomes crossed and then momentarily clears. Under the latter condition it will progress a connection to an accessible local or an accessible incoming selector, depending upon the number of impulses introduced, idly holding such seized selector; in fact, a train of switches may be thus inter-linked.

It will be manifest that the probability for a 105 false single impulse will be greater than for a false series of two, three, and more impulses, in the inverse relation to the number of impulses; at least this is borne out in practice.

All levels of the first selector not used for 110 inter-office trunks may be used for local trunks to local third selectors of the ten-thousand

group containing the concerned first selector. In general, if the first selector is not primarily operated to a level corresponding to a ten-thousand group, the selector will be disabled 5 and a sustained tone applied to the calling line indicative of the condition to prompt the calling party what has occurred, so that he may hang up the receiver to restore the first selector and then initiate a new call. The 10 prompting tone thus serves to educate the subscribers to the more careful removal of the receiver or the more careful handling of switching plugs or keys, where a jack and operator's switching plug or a key is used 15 in place of a telephone and switch-hook.

If the bank level with which the wipers of the first selector have been operated into alignment has the numerically corresponding level position with the numeral indexing 20 the ten-thousand group containing the concerned first selector, the shaft of the first selector will be thereupon caused to restore to normal and prepared to operate rotarilly so that when the said first selector 25 of the connection is re-operated vertically with relation to a level corresponding numerically with the second digit of the called line located in the ten-thousand group containing the concerned first selector, the wipers 30 of the first selector will be automatically rotated in hunting relation and seize a local trunk leading to a local third selector, in readiness for next operating the said third selector by way of extending the call to the 35 connector, in the direction of the called line.

The call to a line of the ten-thousand group containing the concerned first selector will route from the first selector to the local third selector responsive to the second digit; then 40 through the third selector to the connector responsive to the third digit, and through the connector to the called line responsive to the last two digits. However, if the call is to a line of a ten-thousand group reached 45 over an inter-office trunk, the first selector extends the call over an inter-office trunk to an incoming second selector of the ten-thousand group containing the called line, responsive to the first digit, so that the second 50 digit will operate said second selector to seize a trunk local to it extending to a third selector. The third digit will operate the third selector to seize a trunk to the connector; the last two digits then operating the connector 55 to set its wipers on the terminals of the called line; completing the connection.

The first selector will preferably have ten 60 levels corresponding to the digits 1 to 0, so that any level or levels of the first selector not corresponding to a ten-thousand group or groups other than the ten-thousand group to which the concerned first selector belongs may refer to a thousands group of the ten-thousand group to which the concerned first 65 selector belongs. That is, if the system, as

exampled, which has three ten-thousand groups, eight levels of the concerned first selectors of the present invention will be available for local trunks to eight thousands groups of local third selectors. The 70 first selector level numerically corresponding to the first digit of the calling number of the ten-thousand group containing the concerned first selector may thus have local trunks extending to a numerically corresponding thousands group, each trunk of which terminates in a local third selector. The ultimate capacity of a ten-thousand group employing first selectors of the present invention having three ten-thousand groups 75 comprising the system is thus eight thousands groups, or eight thousand lines ultimate capacity. If the system should contain four ten-thousand groups, each ten-thousand group employing first selectors of the present 80 invention would have an ultimate capacity of seven thousands groups. However, where an ultimate capacity of ten thousands is desired from the ten levels, the particular ten-thousand group will have local second 85 selectors introduced between the first selectors and local third selectors, as in general, well known practice.

An object of the present invention, in general, is to guard the system against wrong 90 number calls resultant from careless operating by the calling party. For instance, the false or preliminary digits adverted to, as well as the condition wherein the calling party sends a digit series too soon after an 100 antecedent series to admit of the last selector operated with relation to a level to complete its hunting operation therat. The present invention provides means for disabling a selector against seizing a trunk if the calling 105 dial is operated while the selector is hunting, and to apply a prompting tone to the calling party indicative of the condition. Only the usual relays of the selector are employed in carrying out this function. If the calling 110 party then ignores the said prompting tone and proceeds to annex the series constituting the unsent digits of the called number, the said digits will be to no operative effect. It will be necessary to terminate the call to 115 restore the operative condition of the selector. Reference is made to my Patent No. 1,506,054, granted Aug. 26, 1924.

Reference is also made to my pending applications Serial No. 171,637, filed May 29, 120 1917, and Serial No. 362,321, filed March 1, 1920. It is intended to claim the broader aspects of the subject matter common to these prior applications and the present application in the relationship of the respective filing 125 dates. That is, only subject matter not disclosed in either of these earlier pending applications is intended to be claimed in the present application, although there is subject matter claimed in the said prior pending ap- 130

plications that is disclosed but not intended to be claimed in the present application.

Another object of the present invention is to afford a first selector which in addition to the objects set forth, enables one or more levels thereof to refer to respective thousands of remotely located thousands groups. This will reduce the local thousands capacity of the first selector correspondingly. For example, the system (as exemplified herein) comprises three ten-thousand groups wherein eight levels are available for local use, any number of these so-termed local levels may have the trunks thereof extended outside of the containing building to incoming third selectors in a remotely located building. However, in commercial operation, it would usually be preferred to have the calling numbers of the subscriber lines tributary to said remotely located building have a different index or first digit, so that in the event the connected capacity outgrows the eight levels of the first selector, the said remotely located building will contain numbers reached over inter-office trunks specifically indexed by the first digit. To avoid having to change the calling numbers of lines tributary to said remotely located building, the present invention contemplates that a specific index digit refer to these lines. That is, in the present exemplified system, pulling either digit "4" or "5" initially will operate and then release the first selector and prepare the first selector to select in any level allotted to trunks leading to local or to remotely located third selectors. In the present exemplified system, the first level of the first selector refers to local third selectors and the fourth and the fifth levels refer to remotely located (incoming) third selectors. Manifestly, levels from the sixth to the "0" level inclusive can be chosen at random for trunks extending to local or remote third selectors, wherein pulling either digit "4" or "5" first will prepare the first selector to select a trunk of any level other than the second and third (used for inter-office trunks to incoming second selectors) responsive to the second digit pulled. Thus, pulling digits "45" or "55" will cause the first selector to select in the same level and extend the call in the direction of the same line, determined by the last three digits. This arrangement permits two or more ten-thousand groups to be contemplated and numbers permanently assigned in accordance therewith wherein one or more (two in the present instance) thousand groups will be temporarily operated as subordinate to one of the ten-thousand groups and wherein the inter-office trunks of the latter said ten-thousand groups will also directly serve the thousand groups subordinate thereto. This arrangement thus effects a saving in equipment through the elimination of the incoming second selector in the building containing the

sub-groups, since the trunks leading from the first selectors of the main group lead directly to incoming third selectors in the building to which the sub-group subscribers are tributary. At such time as it is found desirable to make the sub-group a main group, incoming second selectors will be installed antecedent to the incoming third selectors (thereafter operating as local third selectors) and direct inter-office trunks from the respective main offices of the system terminated therein. Local first selectors like FS, FS³ or FS⁵ will then be installed in the converted sub-office for originating traffic as conditions warrant, in view of descriptions to follow.

Outgoing traffic from a sub-office may be handled independently of the incoming traffic, using methods well known, considering the sub-office as a so-called satellite office as to outgoing traffic therefrom, wherein a set of trunks therefrom to a main office of the system is provided, or wherein a direct outgoing inter-office trunk group to each of the main offices is provided.

Another object of the present invention is the means for prompting the user of a busy called line when a call thereto has been selectively made and barred by reason of encountering the called line busy. A briefly applied tone or battery click, or both, to the called line denotes to the user of the called line that connection thereto has been sought. Under the condition, the connection will be terminated as soon as expedient so that the line will probably be found free upon a new attempt to connect with it shortly thereafter. This conduces toward reducing the average holding time of connections, which in turn, reduces the number of connecting links required for handling a given number of calls per unit of time. Reference is made to my U. S. Patent No. 1,506,054, granted Aug. 26, 1924, which discloses a connector with a generally similar object, as well as other devices outside of the connector operated by the connector, having a generally similar object. It will be noted, however, that in the present instance the automatically applied means in the connector applies the tone to the busy called line responsive to encountering the busy condition, and not means in the connector operative responsive to the calling party restoring his receiver, as in the citation. The connector of the present invention does not require additional relays in carrying out this function.

In view of the foregoing general remarks, it will be manifest that the present invention may be employed in a system wherein ten-thousand groups are not equipped with third selectors to the ultimate ten-thousand capacity, gaining the saving of the local second selectors. The concerned ten-thousand group may then be subsequently changed to employ local second selectors at such time

as it is desired to increase the number of thousands groups beyond the first selector capacity, in view of the number of inter-office trunk groups corresponding to remotely located ten-thousand groups of the system. The employment of the present invention thus reduces first cost due to reducing the quantity of equipment links, floor space required, maintenance, depreciation and other charges.

A salient object of the invention concerns that function which precludes the first selector from hunting over a level corresponding to local third selectors responsive to the first directed digit series. The object of this function is to preclude a wrong subscriber's line being called, in the event the calling party carelessly omits the first digit, or omits the letter or name prefix corresponding to the first digit of the number under call. For instance, assume that in the present exemplified system a call is made from a line tributary to the "4" ten-thousand group to called line number "Main-1562," wherein "Main" corresponds to digit "3." Assume further that the calling party neglects to pull the calling dial in correspondence with the prefix "Main" and therefore pulls the first numerically indicated digit "1." The first level of the first selector corresponds to local trunks leading to third selectors represented by third selector B. However, it will appear presently that the first selector will not be enabled to rotate-in on the first level unless the dial has been pulled with correspondence to digit "4," which latter digit indexes the containing ten-thousand group. If this function were not provided, the call would be extended to line "1562" in the "4" ten-thousand office, thus annoying a subscriber not wanted as well as creating the impression in the mind of the calling party that the apparatus functioned improperly. The function last referred to contemplates means for disabling the first selector and applying the prompting tone audible to the calling party if the first digit sent does not index a ten-thousand group. Further, unless five digits are sent, the call cannot be completed to any line, so that if the calling party omits the first digit (or corresponding prefix) and the numerical value of the second digit indexes a ten-thousand group by coincidence, the call will be progressed towards lines embraced by the last four digits of the number when the said four digits are employed as the first four digits, and will not reach a subscriber's line due to lacking the fifth digit to set the final switch upon a subscriber's line. Generally stated, if the first digit (or its equivalent) sent does not index a ten-thousand group, the first selector will be disabled from hunting over a level group of trunks, and therefore, if the first digit indexes a level of the first selector which corresponds to a group of local third

selectors, the first selector will be thereupon disabled from hunting over the corresponding level group. Or it may be otherwise stated that if the first digit sent does not index the ten-thousand group containing the calling line or another ten-thousand group, the concerned first selector will not be enabled to perform a rotary movement at the level attained responsive to the first digit. If the level attained indexes the ten-thousand group containing the first selector, it will restore preparatory to being reoperated to a level at which it will automatically initiate its hunting movement. And if the level attained indexes an inter-office trunk level group the concerned first selector will thereupon hunt thereon to extend the calling line to an incoming second selector in the ten-thousand group or office indexed by the first digit.

The invention has other objects and applications than specifically mentioned. Its scope, as applied to automatic line switching systems in general will be defined by claims annexed.

With reference to the accompanying five sheets of drawings:

Fig. 1 shows a calling telephone CT leading to a line switch LS, the latter having access to a first selector FS of the present invention. The line switch LS and the first selector FS are located in the "4" ten-thousand group, and the first selector FS has access to local third selectors A and B in said Fig. 1, and to incoming second selectors C and D in Figs. 2 and 3, respectively.

Fig. 2 shows a portion of a first selector FS² (of the present invention), which is like the first selector FS, excepting as to the use of a wiper connected to conductor a' (corresponding to conductor a); and bank contacts attached to conductors b' and c' (corresponding to conductors b and c, respectively). The first selector FS² is located in the "2" ten-thousand group and has access to local third selectors E, F and G in said Fig. 2 and to incoming second selectors H and I in Figs. 1 and 3, respectively. The first selector FS² bears the same relation to a line switch (not shown) and calling telephone and line (not shown) as does the first selector FS; the missing conductors and elements of selector FS² being understood as disposed like conductors and elements shown in first selector FS.

Fig. 3 shows a well known selector FS³, modified in accordance with the present invention by the introduction of the rotary off-normal contacts, the tone source and the armature and connections of the series relay. It is accessible from a calling telephone T³ through the line switch LS³. The first selector FS³ is located in the "3" ten-thousand group and has access to local second selector J in said Fig. 3 and to incoming second selectors K and L in Figs. 1 and 2, respectively.

Fig. 4 shows a preferred modification of the lower two shaft-controlled contact sets shown in Fig. 1.

Fig. 5 shows first selector FS⁵, which is a preferred modification of first selector FS.

Fig. 6 is a well known connector C⁶, modified in accordance with the present invention. Incoming third selectors W and X are reached over trunks w and x, respectively, and they have access to connectors Z and C⁶, respectively.

With further reference to the drawings, the incoming second selectors H and K in Fig. 1; local third selectors A, A'', B and M in Fig. 1; incoming second selectors C and L in Fig. 2; local third selectors F, G, G', N and E in Fig. 2; incoming second selectors D and I in Fig. 3; local second selector J in Fig. 3; local third selector P in Fig. 3; incoming second selectors H' and K' in Fig. 5; local third selectors B' and M' in Fig. 5; and incoming third selectors W and X in Fig. 6 are to be assumed as representing selectors like FS³. Connectors Q and R in Fig. 1; S, T and U in Fig. 2; V in Fig. 3; R' in Fig. 5; and Z in Fig. 6 are like connector C⁶ in Fig. 6. The telephone CT, T' and T'' in Fig. 1; T², T²' and T²'' in Fig. 2; T³ and T³' in Fig. 3; T⁵ and T⁵' in Fig. 5; and T⁶ and T⁶' in Fig. 6 are well known automatic telephones of the series type. The line switches LS, LS³, LS⁵ and LS⁶ are well known line switches or finder switches.

First selector FS is like the first selector FS³, excepting for certain changes with reference to the vertical magnet circuit; so-called interrupter relay circuits; shaft-operated contact sets; contacts operated by the so-called release double-dog mechanism, as well as the employment of a vertical off-normal tone source applied through armature of the so-called series relay and a shaft-operated contact set.

First selector FS⁵ is like first selector FS, excepting for the wiring of the so-called series relay and the device for applying interrupted ground to maintain the said relay locked. Other detailed changes in selector FS⁵ will be discussed presently.

Connector C⁶ in Fig. 6 is generally like the connector shown on page 38 of the book "Automatic Telephone Practice", third edition, by Harry E. Hershey, and also shown in Fig. 7 of my pending application for U. S. Patent Ser. No. 535,430, filed Feb. 10, 1922. However, a modification in accordance with the present invention involves the apprising tone source and the uppermost sets of contacts on relays B' and A' and the uppermost resting contact of relay W', as will be discussed presently.

The invention will be comprehended from the following description of assumed calls in the exemplary system.

The sheets containing Figs. 1, 2 and 3 are

to be placed one below the other in numerical order so that the lines extending towards the margins register.

Assume a call from telephone CT to telephone T', the calling number of telephone T' being "44231." Upon removing the receiver from the switch-hook, the line switch LS will operate in the well known manner to extend the calling line to first selector FS. A circuit can now be traced from battery, upper winding of line relay 101, armature 102, conductor 103, wiper of line switch LS, telephone CT, conductor 105, armature 106, lower winding of relay 101 to ground, causing relay 101 to actuate, operatively energizing slow-releasing relay 108 to grounded conductor 109 to maintain the line switch LS. Upon the calling party operating the calling device 112 in correspondence with the first digit "4", the armature 113 will correspondingly vibrate four times to apply its ground through armature 114, sustained armature 115, vertical off-normal (VON) spring 116, slow-releasing series relay 117 to the vertical magnet, designated Vert. M. This will cause the shaft SH carrying wipers 118 to 120 to be set into alignment with the fourth level of bank contacts, having in mind the attracted lower armature of relay 117 will maintain the circuit to the vertical magnet closed after the spring 116 has disengaged consequent to the off-normal movement of the shaft SH.

In this connection, it will be understood that spring-set 121 closes only while the wipers 118 to 120 are in alignment with the fourth level of bank contacts; operated by a projection d of the shaft, having in mind that the first selector FS is located in the "4" ten-thousand group. The spring-set 121 opens upon the shaft rotating-in. It will thus appear that upon relay 117 deactuating, after the last said impulse to the vertical magnet, a circuit path can be traced from grounded conductor 109, armature 122, upper set of vertical off-normal springs, conductor a, spring-set 121, conductor b, armature 123, lower set of vertical off-normal springs, to the release magnet, designated Rel. M. The release magnet will operate its armature e to restore the shaft and to operate the well known so-called double-dog 124 and lock it against retracting under the influence of spring 125, through the agency of the well known so-called release-link 126. The set of springs 127 to 129 is operated by the double-dog 124, so that spring 127 is normally in engagement with spring 129, while spring 128 is normally disengaged, at which position the release link 124 holds the double-dog 126 locked in its operated position through the agency of the projection 130, subject to being unlocked consequent to the attractive movement of the armature f of the vertical magnet, responsive to the first current impulse thereto for stepping the shaft SH off-normal.

In this connection, it will be stated that the double-dog 124, retractile spring 125, release-link 126, and projection 130 correspond to parts b^{22} , b^{26} , f^7 and b^{23} in Figs. 16 and 17 of U. S. Patent No. 815,321, granted to A. E. Keith and J. and C. J. Erickson, March 13, 1906. The mechanical structure of the selectors of the present invention correspond generally to the structure disclosed in the said patent, modified, of course, to operate in accordance with the so-called two-wire principle and in accordance with the present invention. The drawings with reference to the double-dog mechanism, do not purport to disclose the exact mechanical structure, they being simply schematic in order to make the disclosure as simple as possible, but the structure contemplated will be fully understood, in view of the said citation.

It will be thus clear that at the time the release magnet operates its armature e , consequent to the establishing of its described energizing circuit, the spring 117 will disengage from spring 128 and engage spring 129 before the upper set of vertical off-normal springs open, since the shaft SH has not yet had time to restore. That is, ground will be applied from conductor 109, armature 122, upper set of off-normal springs, springs 127—129 to the winding of relay 132 to operatively energize the latter said relay and lock it through armatures 134, 135, 136 to grounded conductor 109 before the shaft has had time to restore to normal. A circuit for the rotary magnet is thus prepared at armature 139, but which is open at spring 128, and this circuit is maintained closed at armature 139 due to the locked condition of relay 132, dependent upon the conductor 109 remaining grounded while the shaft remains at normal, and thereafter until certain operations, as will appear presently, occur.

Upon the second digit "4" being sent from the calling device 112, relay 101 will vibrate four times and relay 117 will attract its armatures while the vertical magnet is again raising the shaft so its wipers are again set to align with the fourth level of bank contacts, the release-link 126 disengaging the projection 130 to allow the double-dog 124 to restore and the spring 127 to disengage from spring 129 and retract against spring 128 consequent to the first operation of the armature f of the vertical magnet. Consequent upon the armature 122 retracting following the fourth impulse to the vertical magnet, a circuit will be closed from grounded conductor 109, armature 122, upper set of vertical off-normal springs, springs 127—128, armature 139 to the rotary magnet, the rotary magnet operating to rotate the shaft one step from normal, incidentally closing the spring set RON and opening the described locking circuit for the relay 132 at armature 135. Wipers 118 to 120 are now in engagement with the first set of

bank contacts 141, 144 and 145, respectively, of the fourth level.

If it is assumed that bank contact 141 constitutes busy-ground, applied in the well known manner by a selector (not shown) companion to selector FS, a circuit can be traced from busy-ground, bank contact 141, wiper 118, armatures 142, 135, RON spring set to the winding of relay 132, the latter said relay re-actuating and locking through armatures 135 and 136 to grounded conductor 109, supplemental to the ground on bank contact 141 applied to armature 135. The before described path from grounded armature 122 to the rotary magnet will now be closed, causing the rotary magnet to rotate the wipers 118 to 120 to the next set of bank contacts, the rotary magnet again operating if the wiper 118 encounters a busy-guarded bank contact. If the wiper 118 rotates into engagement with a bank contact which is not busy-grounded, ground will not be applied to operatively re-energize relay 132. Then, when the armature 136 retracts and the wiper 118 does not receive ground from an engaged bank contact, a circuit can be traced from grounded conductor 109, winding of relay 143, armature 135, spring set RON, winding of relay 132 to grounded battery, the relay 143 actuating to thereby effect the seizure of the selector FS, while the armatures of relay 132, due to its marginal adjustment, remain retracted. Thus, if it is assumed that the wiper 118 did not encounter busy-ground on bank contact 141, the calling line will be extended to third selector A consequent to selector FS seizing by the actuation of relay 143.

The third selector A will operate in the well known manner, in view of the present invention, as will appear, to seize the connector Q, responsive to the sending of the third digit "2" from the calling device 112, and the connector Q will operate in the well known manner, in view of the present invention, as will appear presently, responsive to the sending of the last two digits "31" from the calling device 112, to set the wipers upon the called line leading to telephone T'. The called telephone T' will be signaled in the well known manner, and the selector FS and the line switch LS will be maintained from ground applied back from the connector Q. The call will be destroyed in the well known manner, having in mind that the effective circuits of selector FS are equivalent to those of selector A after its seizure. That is, when ground is removed from conductor 109 resultant to the deactuation of the so-called release relay of the connector Q, the relay 143 will deactuate, whereupon a circuit can be traced from grounded armature 113, armatures 114 and 115, lower set of vertical off-normal springs to the release magnet, its armature e operating to restore the shaft SH and lock the double-dog 124 into the position shown in the

drawing. The double-dog is locked by the projection 130 cooperating with opening in the release link 136.

The call described was to telephone T' belonging to the ten-thousand group to which the calling telephone CT belongs. It is noted that the first digit "4" was not effective to cause a completed linking operation; it only serving to set-up a specific preparatory condition in the first selector FS. The second digit "4" effected a linking operation to a local third selector A, so that but two directive linking switches are required to complete the connection beyond the first selector, whereas five digits are employed, the first digit being absorbed, as it were, by the restoration of the shaft of first selector FS.

It will now be assumed that the calling party inadvertently introduced a preliminary impulse constituting the digit "1" through carelessly opening the circuit including relay 101 for a brief period by the switch-hook. The wipers 118 to 120 will thus be aligned with the first level of bank contacts. However, it will be noted that the set of springs 121 are not operated to cause the release magnet to restore the shaft and to cause the relay 132 to actuate and lock, as when the shaft was assumed aligned with the fourth level. Under this condition, the rotary magnet will not operate due to the armature 139 being in its normal position. The set of springs 147 (which closes on off-normal vertical positions and opens on rotating-in at all levels) thus remains closed so that tone from the indicated source in Fig. 1 will be applied through spring set 147, armature 148 to armature 106, audible to the calling party, to apprise him of the condition existing, the call being vitiated. The calling party will replace the receiver, causing relays 101 and 108 to deactivate in sequence to close the described path from armature 113 to the release magnet to restore the circuits, preparatory for a new call. It will be noted in this connection that if the calling party ignores the said tone and he then sends the first digit "4" of the line under call, no effect will result from the vibration of the armature 113 of line relay 101, due to the vertical off-normal spring 116 being disengaged and the lower armature of series relay 117 being retracted; the vertical magnet being thus disabled. It will also be noted that in normal operation, a circuit will be closed from the tone source through the spring set 147, armatures 148 and 106 to conductor 105, but the duration of this tone, pending the rotating-in of the shaft SH will be so brief that it will not cause confusion, and in fact, the armature 148 may be adjusted to retract after armature 122, to reduce the period of application of the tone to conductor 105 under normal operation. Moreover, the brief application of the tone will be indicative of the normal operation of the selector FS.

Had the stated call been to telephone T'', the telephone number of which is "41321", in lieu of telephone T', the second digit "1" would cause the first selector FS to have selectively operated as described, but with relation to the first level (in lieu of the fourth) to seize third selector B, the call being completed by annexing the last three digits "321", in the manner before described. The same would apply wherein the second digit refers to a level above the fourth (not indicated), the first, fourth, and all levels above the fourth being reserved for "thousands" trunks to respective groups of local third selectors; each of said thousands groups indexed by the numerical off-normal position of the level of the first selector FS corresponding.

The spring set 151 is adjusted to close when the wipers 118 to 120 align with the second and also the third level of bank contacts; operated by projections *h* and *i*, respectively. These latter stated levels correspond to inter-office ten-thousands trunk groups leading to groups of incoming second selectors in respective, numerically corresponding ten-thousand groups other than the one containing the calling line from telephone CT and first selector FS.

If it is now assumed that the call was to telephone T'' in the "2" ten-thousand group, the calling number of which is "22341", the first digit sent would be "2", causing the wipers 118 to 120 to be set into alignment with the second level of bank contacts. Due to the said adjustment of the spring set 151, when armature 122 retracts, ground from conductor 109 is applied through upper set of vertical off-normal springs, conductor *a*, spring set 151, conductor *c*, to the winding of relay 132, the latter said relay actuating and locking in the manner before described, the armature 139 closing a path from grounded conductor 109, armature 122, upper set of vertical off-normal springs, springs 127-128 to the rotary magnet. The rotary magnet will thus start the described hunting operation when the wipers have been set into alignment with the second level of bank contacts, upon the armature 122 retracting during the said aligned condition. If the first inter-office trunk *j* of the second level (leading to the "2" ten-thousand group) is idle, the incoming second selector C connected to the said first trunk will be seized thereover, and if the said trunk assumed seized is busy, the first successive idle trunk (not shown) of the second level leading to a second selector companion to the said selector C will be seized. The sending of the last four digits "2341" will cause the call to be progressed through incoming second selector C, third selector N and connector U to the called telephone T'', in the well known manner, in view of the present invention, as will appear presently.

In the last foregoing assumed call, had the first digit been "3", in lieu of "2", the first selector FS would operate as last described, but with relation to the third level, and seize 5 the inter-office trunk h leading to second selector D, or a trunk (not shown) of its group. If the call were to telephone T^3 , the telephone number of which is "32321", annexing the last four digits "2321" will cause the call 10 to be progressed through said incoming second selector D, third selector P and connector V to the called telephone T^3 , in the well known manner, in view of the present invention, as will appear presently.

15 It will be understood that the single line representing an inter-office trunk may refer to two conductors or three conductors, depending upon if a repeater or other circuit translating device is or is not employed in the 20 trunk. However, the inter-office trunks are disposed in the well known manner from the banks of the first selector FS (and also first 25 selectors FS^2 , FS^3 and FS^5). The local trunks from the banks of the first selectors FS (and also first selectors FS^2 and FS^5) are disposed in the well known manner for connecting trunks from the banks of second 30 selectors. That is to say, the trunks to the local third selectors and to the incoming 35 third selectors in the satellite lead from the banks of the first selectors of the present invention as if it were a local second selector in well known systems, while the inter-office trunks lead from the banks of the said first 40 selectors to incoming second selectors as heretofore practiced; the local second selectors being dispensed with.

If the first digit sent does not cause spring set 121 or spring set 151 to operate; that is, 45 if the first digit is not "4" to correspond to the ten-thousand group containing the concerned first selector, and also is not "2" or "3" to correspond to the other ten-thousand groups of the system, the interrupter relay 132 will not be caused to operate, so that the indicated tone source will be sustainingly applied audible to the calling party, as if the digit sent was the result of a false or so-called preliminary series accidentally introduced. 50 In view of previous descriptions, it is manifest that when first selector FS (or FS^2) is operated as last described, the vertical magnet is disabled through the retraction of lower armature of relay 117 and the disengaging of spring 116, so an impulse applied 55 from the armature of line relay 101 will not be thereafter effective unless the call has first been effaced.

It will be manifest that other levels than 60 the second and third shown may be set apart for the inter-office trunks to incoming second selectors of respective numerically corresponding ten-thousand groups, correspondingly limiting the capacity of the ten-thousand group to which the concerned first se-

lector belongs. Moreover, this limiting of capacity will concern all other ten-thousand groups of the system having first selectors from which trunks of two numerical orders lead, as to incoming second selectors and to 70 local third selectors, since trunks will (as shown) mutually lead from all first selectors to incoming second selectors of all ten-thousand groups.

The trunk arrangement commonly practiced shown in Fig. 3, may be employed where the ultimate ten-thousand group capacity is required subsequently. That is, to change the "4" ten-thousand group to correspond to the well known trunking practice 75 disclosed in Fig. 3, a group of selectors like FS^3 will be substituted for the group of selectors like FS. Then, the local trunks which lead-out from the levels of the group of selectors to which selector FS belonged, 80 will be attached to corresponding levels of a group of newly installed local second selectors of the same type as the said newly installed first selectors. The inter-office trunks will be connected to levels of the newly installed 85 first selectors to correspond to the former connection. Then, local trunks will lead from the corresponding level of the said newly installed first selector group (the fourth in the 90 present instance) to the said newly installed 95 second selectors. This will apply to all local trunk levels of the first selector.

The present invention thus lends itself where a multi-office system is desired, but 100 wherein the ultimate capacity of ten-thousand lines in one or more of the offices or so-termed ten-thousand groups is not required to be more than ten-thousand, less as many thousands as the number of ten-thousand groups employed in the system other than 105 the office concerned.

The operation of the first selector FS^2 will 110 be clearly understood in the light of the foregoing detailed descriptions relating to first selector FS, having in mind that the corresponding parts shown in first selector FS^2 are similarly designated as in first selector FS, but with a prime added, and that the parts shown in first selector FS^2 cooperate 115 with parts (not shown) which are like the corresponding cooperating parts in first selector FS. However, a mechanical detail of selector FS^2 is modified wherein an added wiper 201 and cooperating bank contacts are 120 substituted for the spring sets 121 and 151 125 of selector FS. The first selector FS^2 is located in the "2" ten-thousand group, the third and fourth bank levels thereof having inter-office trunks m and n leading therefrom to incoming second selectors I and H, respectively, 130 of numerically corresponding ten-thousand groups, and the second level having local trunks leading to local third selectors, as selector F. Wiper 201 normally engages a bank contact at each level position of the

- shaft carrying wipers 118' to 120', but disengages its engaged bank contact upon a rotary movement of the shaft. It will thus be clear that if the selector FS² is operated so 5 its wipers 118' to 120' are set into alignment with the second bank level responsive to sending first digit "2" in calling telephone T², for instance, a circuit will be completed from grounded conductor 109', armature 122', up- 10 per set of vertical off-normal springs, conductor a', wiper 201, bank contact 202, conductor b', armature 123', lower vertical off-normal spring set to the release magnet (not shown) to lock the double-dog 124' and to 15 restore the shaft to normal to cause the relay 132' to actuate and lock as described with reference to selector FS. The next (second) digit "2" sent will then reoperate the shaft SH' and set the wipers thereon into alignment with 20 the second bank level, corresponding to local trunks. The release magnet will not now operate, due to armature 123' being attracted. The rotary magnet, designated Rot. M', will 25 operate to advance the wipers 118' to 120' over the second level in automatic selective or hunting operation, incidentally closing the rotary off-normal spring set RON' for the object described with reference to spring set RON in selector FS.
- 30 Had the shaft of selector FS² been primarily operated with relation to the third or fourth level (corresponding to inter-office trunks), the relay 132' would have actuated and locked from ground applied from conductor 109', armature 122', upper set of vertical off-normal springs, conductor a', wiper 201, bank contact 203 or 204, conductor c' to the winding of relay 132', and the ground from grounded conductor 109' will be then 35 also applied through armature 122', springs 127'-128', armature 139' to the rotary magnet to rotate the wipers 118' to 120' and operate spring set RON' so that the automatic selective or hunting operation may continue 40 45 as described with relation to selector FS when functioning on the second and the third levels.
- It will be manifest that if the shaft of selector FS² is set with relation to levels not numerically corresponding to a ten-thousand 50 group (the fifth level, for example), no circuit will be completed to energize the interrupter relay 132', so the shaft will be thereupon disabled from thereafter rotating-in or being raised vertically in the manner set forth 55 with respect to selector FS.
- Local calls through selector FS² to telephone T², T²', and T²'' will be completed by first setting the shaft of selector FS² into alignment with the second level, from which 60 position the shaft will be automatically restored, since selector FS² is in the "2" ten-thousand group. Then, annexing the last four digits of the corresponding telephone number, depending upon which telephone is 65 called, will complete the call, the operation

being manifest in view of the foregoing descriptions and statements.

Inter-office calls to telephone T³ in Fig. 3, from a calling line through any of the first 70 selectors FS, FS² or FS³ will be clear, in view of previous descriptions and statements.

Extending a call from telephone T³ to telephone T³' will be effected in the well known manner (in view of the present invention) by successively operating first selector FS³ to 75 the third level; local second selector J to the second level; third selector P to the third level; and connector V to the second level and then in one step.

It will be noted in this connection that: The 80 inter-office trunks p and q lead from the fourth and second levels of selector FS³ to incoming second selectors K and L, respectively; that third selector A" in Fig. 1 is accessible from the fourth levels of incoming 85 second selectors H and K in a call over either of the inter-office trunks n and p; that connector S in Fig. 2 is accessible from the fifth levels of incoming second selectors C and L and the second level of selector E; that third selector G' in Fig. 2 is accessible from the first 90 levels of incoming second selectors C and L; and that connector T is accessible from the third level of third selectors G and G'.

Selector FS³ is generally like the selector 95 shown on page 60 in the cited book by Hershey, so that its normal operation need not be detailed for a complete understanding of its general operation. However, the present invention comprehends the addition of 100 two armatures on relay 317 an indicated tone source and circuits associated with the said armatures drawn slightly heavier than other control circuits to distinguish them. The operation as contemplated by the present invention is as follows: If the calling party at telephone T³ operates the calling device while the selector FS³ is hunting, the armature 313 of line relay 301 will apply ground through 105 armatures 314, 315, winding of relay 317 to 110 the vertical magnet, armature 353 attracting to lock relay 317 from battery derived through the vertical magnet, resistance 354, rotary off-normal spring set RO³, winding of tone transformer 355 to ground. The resistance 354 will restrict the current below the operative value of the vertical magnet, but not below the sustaining requirement of relay 317. The tone will be applied through armatures 356 and 306, audible to the calling party, 115 120 indicative of the condition. Armature 322 being attracted, operatively energizes the winding of relay 332, so that armature 336 applies ground to the upper winding terminal of switching relay 343 to maintain it disabled. The attracted armature 322 also disables the 125 rotary magnet. That is, if armature 313 retracts while selector FS³ is hunting, the selector will become disabled from thereafter hunting, or of seizing by the actuation of re- 130

lay 343. The circuits will be restored upon replacing the receiver at the calling telephone to deenergize relay 301 and thereby close the energizing circuit of the release magnet. It 5 will be manifest that the selectors like FS³, used as second and third selectors will operate similarly so far as becoming disabled if the calling party operates the calling device while the concerned selector of the connection is 10 hunting.

By joining the sheet containing Fig. 6 to the right of the sheet containing Fig. 5 so that the lines extending to the adjacent margins register, and then substituting the sheet containing Fig. 5 (while attached to the sheet containing Fig. 6) for the sheet containing Fig. 1, a preferred organization is attained. It will be noted that calls to the telephones shown on sheets containing Figs. 2 and 3 will be reached 15 over the same inter-office trunks from the sheet containing Fig. 5. Also, that the telephone T''⁵ may be reached over switch links of Fig. 5 corresponding to switch links B, R, M, K and H, shown in Fig. 1, used in connecting to telephone T'', having in mind the corresponding links have a prime added to their designation letter. The trunks j⁵, k⁵, n⁵ and p⁵ in Fig. 5 correspond to j, k, n and p in Fig. 1, respectively. Designation numerals 20 in Fig. 5 correspond to similarly disposed parts in Fig. 1, but have digit "5" for the first digit in lieu of "1".

The general operation of selector FS⁵ will be understood from the descriptions with respect to Fig. 1. However, the modifications 25 will be explained in view of their objects.

The ten-thousand group containing selector FS⁵ has a satellite or sub-office located in a building remote from the building containing selector FS⁵. That is, the thousands groups of trunks leading from the fourth and the fifth levels of selector FS⁵ (and its companion selectors), represented by trunks w and x are inter-sub-office trunk groups rather than 30 local trunk groups, as are the trunks leading from the fourth level of selector FS, wherein selector A represents a group of local third selectors reached over the fourth level. The trunks w and x may each have a well known 35 so-called trunk repeater interposed at the originating end to translate from three-conductor to two-conductor operation for the inter-office section. The calling of a number from telephone T⁵ will cause the selector FS⁵ to operate the same in selecting on level 40 "1" or levels "4" and "5", having in mind that eight levels (being all but the second and third levels used for inter-main-office trunks) may be interchangeably used for local or 45 satellite connections without altering the selector functional operation.

As understood from statements made at the outset, the selector FS⁵ will be employed where the local and satellite capacity combined for the ten-thousand group containing

selector FS⁵ will not exceed eight thousands; divided as the exchange layout warrants. This is assuming there are two levels reserved for inter-ten-thousand group trunks. Under this condition, the first digit sent will 70 determine the ten-thousand group as in the case of selector FS, but wherein the second digit, if the selector restores its shaft responsive to the said first digit, will determine if the call will be extended to the satellite 75 or will be a local one; the same number of switch links being employed in either instance, since it will be noted that the trunks w and x terminate in incoming third selectors W and X, respectively. 80

In the last exemplified instance, the shaft SH⁵ will be automatically restored if primarily aligned with either the fourth or the fifth level, so that pulling an initial digit "4" or "5" will have the same operative value 85 and effect and may therefore be pulled interchangeably where the listed number has digit "4" or "5" as the first digit thereof. This is provided, as adverted to at the outset, so that the first digit of the calling number will be 90 specific to the lines directly tributary to the building containing selector FS and to the building containing the satellite, respectively.

Of course, it will be understood that the trunk group represented by trunks w and x may 95 each (group) refer to a specific satellite, in place of both referring to the same satellite. That is, in place of the satellite having a capacity of two thousand lines, two satellites of one thousand lines each may be concerned. 100 Moreover, each of the levels above the fifth may refer to a specific satellite of one thousand lines capacity or a lesser number of satellites with a total capacity of five thousand lines in level combinations as arbitrarily 105 chosen and combined. And, in fact, level "1" may refer to a satellite of one-thousand lines capacity.

The exemplified instance assumes that the satellite corresponding to the fourth and the 110 fifth levels may at a future time be converted into a main or ten-thousand group. At such time, the shaft projection y⁵ will be moved on the shaft to operate spring set 551 in lieu of spring set 521. Then, a group of inter-office trunks leading to incoming second selectors having access to both the third selector 115 groups W and X will be substituted for the satellite trunks w and x. Under this condition the latter said substituted inter-office 120 trunks will lead from the fifth level, thus leaving the fourth level of selector FS⁵ dead and available for local one-thousand capacity, or for a satellite one-thousand capacity 125 wherein the first digit of the telephone number thereof will be "4". Or, a projection for operating the spring set 521 at any other level not chosen for inter-office trunks may be introduced on the shaft SH⁵ so the shaft may then be operated with relation to the 130

fourth level or with relation to the said chosen level, to cause the selector FS⁵ to release and then be operated over a level other than inter-office trunk levels (but including the 5 fourth and the said chosen level) to reach a local or satellite level interchangeably, for the object set forth with reference to the fourth and fifth levels wherein projections d⁵ and y⁵ are employed.

10 It will be clear, from the foregoing, that in calling telephone T⁶ or telephone T⁶, the first digit may be either "4" or "5" interchangeably. Further, since they refer to the "5" ten-thousand group of numbers, they may 15 be segregated by introducing a group incoming second selector antecedent to selectors W and X leading from the fifth level of selector FS⁵; the projection y⁵ being changed to operate spring set 551 at the fifth level position of 20 the shaft SH⁵. It will also be clear, in this connection, that any other levels above the fifth could have been chosen for the trunk groups w and x without changing the projections d⁵ and y⁵, but in that event the thousands 25 of the satellite reached over the trunks w and x will numerically correspond to the last said levels of selector FS⁵ chosen.

It will be noted that the relay 517 is included in a path directly from the make contact of 30 armature 515, in lieu of through a spring corresponding to 116 in Fig. 1. In the event the armature 513 of line relay 501 is caused to retract while the selector FS⁵ is hunting, ground will be applied through armatures 35 514, 515, winding of relay 517 to the vertical magnet, effective to attract armature 553. A locking circuit of relay 517 will be established through the vertical magnet, winding of relay 517, resistance 554, armature 553, rotary off-normal springs of set RO⁵ to interrupted 40 ground source 555. The resistance 554 is of such value as will restrict the current below the operative value of the vertical magnet, but not below the sustaining value of relay 517. The interrupted ground will serve to 45 maintain the relay 517 actuated (due to its characteristic of sustaining over brief current lapses, because of being slow-releasing) and at the same time apply the interrupted ground 50 through armatures 548 and 506, audible to the calling party, indicative of the condition. Under this condition, armature 522 applies ground to the conductor leading to the upper winding terminal of relay 543 to maintain it 55 disabled, so the selector cannot seize; the rotary magnet being disabled due to the attracted condition of armature 522.

The tone source shown in Fig. 5 is applied 60 through spring set 547, armatures 557, 548 and 506, audible to the calling party, if the shaft SH⁵ is raised so its wipers align with a level at which spring set 551 or 521 is not operated to cause relay 532 to actuate and lock. That is, since spring set 547 will close 65 at off-normal vertical positions, unless the

operation of the selector has been normal, armature 557 will remain retracted after armature 522 retracts to cause a sustained tone application audible to the calling party. A brief tone application before the armature 557 70 has time to attract will not be indicative of a disabled condition, in view of the description of selector FS, but on the other hand, will be indicative of the normal effective operation of the selector.

The general operation of connector C⁶ will be clear in view of the citation. The modification of the connector contemplated by the present invention is indicated by the lines drawn slightly heavier than other operating conductors to distinguish them. When the connector C⁶ is selectively set up on a busy called line the indicated apprising tone source will be applied through armatures 601, 602, 603, wiper 604 to the 80 engaged bank contact of the called line, audible to the user thereof to indicate the condition. The detailed operation is as follows: Relay B', which is the so-called busy relay, actuates consequent to the test wiper 85 605 encountering busy-ground in the test contact, which closes the last described tone path and maintains it until armature 602 retracts, the releasing period of relay A' after the impulses to the rotary magnet cease. The 90 switch-arm 606 may be manually set to apply grounded battery through retardation coil 607 to supplement the tone applied by the said source. The relay B' has an added lower winding in series with the winding on relay 100 A'. This added winding energizes the core of relay B' in opposition to the upper winding so when the wiper 605 passes over busy grounded bank contacts in reaching the test contact of the called line the lower winding 105 will energize to tend to prevent the operative attraction of armature 601. The said lower winding will not in itself operatively attract armature 601, due to the adjustment of armature 601, but it exerts sufficient tractive effort 110 to prevent the upper winding doing so. However, after the wiper 605 is set upon a busy-grounded bank contact for a slightly prolonged period, the lower winding of relay B' being then unenergized, the upper winding 115 will operatively energize. The conductor leading from armature 609 includes a set of added normally closed contacts 610; operated by the armature of the rotary magnet consequent to its initial movement to further disable relay B' from operating while passing over busy-grounded bank contacts to the busy-test contact of the line under call. This is to insure that disturbance will not be applied to a passed-over busy line. It will thus be clear 125 that a brief tone, or a tone and battery click, will be applied audible to the user of a busy called line, upon a connector being operated into testing relation therewith and finding it barred. It will be manifest that the relay 130

B' may be given a slightly stiff adjustment, or be slugged to retard its actuation, and the relay A' given a more pronounced slow-releasing characteristic, by way of prolonging the application of the tone.

With reference to Fig. 4, which shows a preferred embodiment of the shaft-operated spring sets 121 and 152, the spring set 121 operated by projection *d* and the spring set 151 operated by projections *h* and *i*, are arranged so that an insulated element of the double-dog 124 disables the said spring sets when the shaft is in its operation from normal or its restoration to normal. When it is at normal, the double-dog is locked by the release link 126. The object of this provision is to permit the shaft to restore freely, due to the said spring sets being flexed out of line with the said shaft projections.

In the foregoing, a so-called hundred-thousand line or five-digit ultimate capacity system was contemplated. It will be manifest that the present invention can be also applied to other capacity systems; so-called four-digit or ten-thousand line ultimate capacity systems, for example. The application of the present invention to the four-digit system would be as disclosed with reference to the five-digit system, assuming that the inter-office trunks would extend to second selectors having direct access to connectors, and that local trunks from the first selectors would extend to connectors, there being no third selectors.

It will be manifest that the first selector FS (and also FS² and FS⁵) may be employed as a first selector in a so-called ten-thousand line system wherein there is but a single office. This application is particularly advantageous if the capacity of the system necessitates the use of the "1" and "2" levels, which are particularly subject to the referred-to false selection by reason of the so-called preliminary impulses, accidentally applied. Under this application of the invention, the levels below the fourth, for instance, will not be subject to selection, unless the shaft of the selector is first operated with relation to the third level and restored through the agency of the projection *d*, set to operate the spring set 121 at the third level. The contact set 151 will then be adjusted to be operated at all levels above the third. This will entail five-digit numbers where a line under call is reached over a level below the fourth. The first digit "3" will be effective to operate and restore the shaft and actuate and lock the relay 132, preparatory to a level-hunting operation responsive to the second digit being sent to reoperate the shaft into alignment with a level below the fourth. That is, it will be necessary to send a preliminary digit "3" to capacitate the first selector for hunting over a level below the fourth. Manifestly, this may be applied to so-called hundred-thousand line systems. Under this

application the levels below the fourth cannot be hunted over unless a preliminary digit "3" has been sent as before; making six digits in all. Of course, any other level than the third may be chosen, but to gain the advantages of the function it should be above the first level.

The term "selector" used in certain of the claims is to be understood as comprehending any selective switch, that is, a switch which operates to select an accessible line.

The scope of the invention will be defined by subjoined claims.

I claim:—

1. In an automatic telephone system, a selector, switch means for connecting to the selector, relays for operating the selector, a group of line terminals accessible from the selector, remote control means operated at will after the selector is connected with for causing the operation of the relays to set the selector into hunting relation to the line terminals and seize the first idle one encountered, and relay operated means comprising only said relays for disabling the selector from seizing responsive to the control means being operated while the selector is hunting.

2. In an automatic telephone system, a wiper selector, switch means for connecting to the selector, relays of the selector, a group of line terminals accessible from the selector, remote control means operated at will after the selector is connected with for causing the operation of the relays to set the selector into hunting relation to the line terminals and seize the first idle one encountered, and relay operated means comprising only said relays for disabling the selector from seizing responsive to the control means being operated while the selector is hunting.

3. In an automatic telephone system, a wiper selector, switch means for connecting to the selector, relays of the selector, a group of line terminals accessible from the selector, remote control means operated at will after the selector is connected with for causing the operation of the relays to set the selector into hunting relation to the line terminals and seize the first idle one encountered, and relay operated means comprising only said relays for disabling the selector from continuing its hunting operation responsive to operating the control means while the selector is hunting.

4. In an automatic telephone system, a wiper selector, relays of the selector, a group of line terminals accessible from the selector, remote control means for causing the energizing and deenergizing of the relays to set the selector into hunting relation to the line terminals and seize the first idle one encountered, and relay means comprised only of said relays for disabling the selector from continuing its hunting operation responsive to operating the control means while the selector is hunting.

5. In an automatic telephone system, a wiper selector, relays of the selector, a group of line terminals accessible from the selector, remote control means for causing the energizing and deenergizing of the relays to set the selector into hunting relation to the line terminals and seize the first idle one encountered, and relay means comprised only of said relays responsive to the control means for stopping the hunting operation without restoring the selector. 70
6. In an automatic telephone system, a calling line, a selector terminating the calling line, switch means for connecting to the calling line, relays for operating the selector, a group of line terminals accessible from the selector, control means operated over the calling line at will only after the calling line is connected with by the switch means for causing the operation of the relays to set the selector into hunting relation to the line terminals and seize the first idle one encountered, and relay means comprising only said relays operated for disabling the selector from seizing responsive to the control means being operated while the selector is hunting. 75
7. In a telephone system, a calling line, a selector terminating the calling line, switch means for connecting to the calling line, relays of the selector, a group of line terminals accessible from the selector, directive control means on the calling line at will only after the calling line is connected with by the switch means for operating certain of the relays to set the selector with selective relation to the group, means for causing certain of the relays to thereafter operate the selector in hunting relation with the group and seize the first idle terminal found, and relay means comprising only said before operated relays operated for disabling the selector from seizing responsive to the control means being operated while the selector is hunting. 80
8. In a telephone system, a calling line, a selector terminating the calling line, switch means for connecting to the calling line, relays of the selector, groups of line terminals accessible from the selector, directive control means on the calling line at will only after the calling line is connected with by the switch means for operating certain of the relays to set the selector with selective relation to a desired group, means for causing certain of the relays to thereafter operate the selector in hunting relation with the group and seize the first idle terminal found, and relay means comprising only said before operated relays operated for disabling the selector from seizing responsive to the control means being operated while the selector is hunting. 85
9. In a telephone system, a switch, primary and secondary driving magnets for the switch, a group of line terminals accessible from the switch, automatic means for operating the primary magnet to drive the switch with selective relation to the group, means for causing the secondary magnet to operate to drive the switch with connective relation to the first terminal of the group, and directive controlled means operated before the first said operation for rendering the secondary magnet responsive to automatically applied means to drive the switch responsive to the first said operation. 90
10. In a telephone system, a switch, primary and secondary driving magnets for the switch, a group of line terminals accessible from the switch, automatic means for operating the primary magnet to set the switch with selective relation to the group, means for operating the secondary magnet for causing the switch to hunt over the terminals of the selected group, directive controlled means including the primary magnet operated before the first said operation for rendering the hunting operation automatically applied responsive to the first said operation, and means for normally barring the switch from operating its secondary magnet until the last said means is operated. 95
11. In a telephone system, a switch, primary and secondary driving magnets for the switch, a group of line terminals accessible from the switch, automatic means for operating the primary magnet to drive the switch with selective relation to the group, means for causing the secondary magnet to operate to drive the switch with connective relation to the first terminal of the group, and directive controlled means operated before the first said operation for rendering the secondary magnet responsive to automatically applied means to drive the switch responsive to the first said operation. 100
12. In a telephone system, a switch, primary and secondary driving magnets for the switch, a group of line terminals accessible from the switch, automatic means for operating the primary magnet to drive the switch with selective relation to the group, means for causing the secondary magnet to operate to drive the switch with connective relation to the first terminal of the group, directive controlled means operated before the first said operation for rendering the secondary magnet responsive to automatically applied means to drive the switch responsive to the first said operation, and means for maintaining the switch in the first said operated condition if the directive controlled means is not operated. 110
13. In a telephone system, a switch, primary and secondary driving magnets for the switch, a group of line terminals accessible from the switch, automatic means for operating the primary magnet to drive the switch with selective relation to the group, means for causing the secondary magnet to operate to drive the switch with connective relation to the first terminal of the group, directive controlled means operated before the first said operation for rendering the secondary magnet responsive to automatically applied means to drive the switch responsive to the first said operation, and means for maintaining the switch in the first said operated condition if the directive controlled means is not operated. 115
14. In a telephone system, a switch, primary and secondary driving magnets for the switch, a group of line terminals accessible from the switch, automatic means for operating the primary magnet to drive the switch with selective relation to the group, means for causing the secondary magnet to operate to drive the switch with connective relation to the first terminal of the group, directive controlled means operated before the first said operation for rendering the secondary magnet responsive to automatically applied means to drive the switch responsive to the first said operation, and means for maintaining the switch in the first said operated condition if the directive controlled means is not operated. 120
15. In a telephone system, a switch, primary and secondary driving magnets for the switch, a group of line terminals accessible from the switch, automatic means for operating the primary magnet to drive the switch with selective relation to the group, means for causing the secondary magnet to operate to drive the switch with connective relation to the first terminal of the group, directive controlled means operated before the first said operation for rendering the secondary magnet responsive to automatically applied means to drive the switch responsive to the first said operation, and means for maintaining the switch in the first said operated condition if the directive controlled means is not operated. 125
16. In a telephone system, a switch, primary and secondary driving magnets for the switch, a group of line terminals accessible from the switch, automatic means for operating the primary magnet to drive the switch with selective relation to the group, means for causing the secondary magnet to operate to drive the switch with connective relation to the first terminal of the group, directive controlled means operated before the first said operation for rendering the secondary magnet responsive to automatically applied means to drive the switch responsive to the first said operation, and means for maintaining the switch in the first said operated condition if the directive controlled means is not operated. 130

for causing the secondary magnet to operate to drive the switch with connective relation to the first terminal of the group, directly controlled means operated before the first 5 said operation for rendering the secondary magnet responsive to automatically applied means to drive the switch responsive to the first said operation, and means for maintaining the secondary magnet of the switch disabled from operating if the last said means is not operated.

14. In a telephone system, a switch, primary and secondary driving magnets and a release magnet for the switch, groups of line 15 terminals accessible from the switch, automatic means for operating the primary magnet to set the switch with selective relation to a desired group, means for operating the secondary magnet for causing the switch to hunt 20 over the terminals of the selected group, directly controlled means including the primary magnet and the release magnet operated before the first said operation for operating and restoring the switch and for rendering the hunting operation automatically applied responsive to the first said operation, and means for maintaining the switch in the first said operated condition if the last said means is not operated.

30 15. In a telephone system, a switch, primary and secondary driving magnets and a release magnet for the switch, groups of line terminals accessible from the switch, automatic means for operating the primary magnet to set the switch with selective relation to a desired group, means for operating the secondary magnet for causing the switch to hunt over the terminals of the selected group, directly controlled means including the 35 primary magnet and the release magnet operated before the first said operation for operating and restoring the switch and for rendering the hunting operation automatically applied responsive to the first said operation, means for maintaining the switch in the first said operated condition if the last said means is not operated, and a signal device rendered operative consequent to the said disablement.

50 16. In a telephone system, a switch, primary and secondary driving magnets and a release magnet for the switch, groups of line terminals accessible from the switch, automatic means for operating the primary magnet to set the switch with selective relation to a desired group, means for operating the secondary magnet for causing the switch to hunt over the terminals of the selected group, directly controlled means including the primary magnet and the release magnet operated before the first said operation for operating and restoring the switch and for rendering the hunting operation automatically applied responsive to the first said operation, 65 and means for disabling the secondary mag-

net from operating if the last said means is not operated.

17. In a telephone system, a switch, a plurality of groups of line terminals, primary and secondary driving magnets for the 70 switch, automatic means for directly operating the primary magnet to drive the switch into selective relation to a desired said group, automatically applied means for causing the secondary magnet to drive the switch over 75 the terminals of the selected group, and means depending upon what group the switch is driven into selective relation to for thereupon disabling the secondary magnet from thereafter operating.

80 18. In a telephone system, a switch, a plurality of groups of line terminals, primary and secondary driving magnets for the switch, automatic means for directly operating the primary magnet to drive the 85 switch into selective relation to a desired said group, automatically applied means for causing the secondary magnet to drive the switch over the terminals of the selected group, means depending upon what group the switch is driven into said selective relation to for thereupon disabling the secondary magnet from thereafter operating, and a signal device rendered operative consequent to the said disablement.

90 19. In a telephone system, a calling line, a tone source, a calling device on the calling line, a switch, a plurality of groups of line terminals, primary and secondary driving magnets for the switch, automatic means for directly operating the primary magnet to drive the switch into selective relation to a random said group, automatically applied means for causing the secondary magnet to drive the switch over the terminals of the 95 said selected group, and means depending upon what group the switch is driven into said selective relation to for thereupon disabling the secondary magnet from thereafter operating and for applying the tone source 100 to the calling line.

105 20. In a telephone system, a switch, a plurality of groups of line terminals, primary and secondary driving magnets for the switch, directive means for automatically operating the primary magnet to drive the switch into selective relation to a random said group, automatically applied means for causing the secondary magnet to drive the switch over the terminals of the selected group, means depending upon what group the switch is driven into said selective relation to for thereupon disabling the secondary magnet from thereafter operating, and means dependent upon 115 operating the switch by the primary magnet 120 to a predetermined group for disabling the last said means.

125 21. In a telephone system, a switch, a plurality of groups of line terminals, primary and secondary driving magnets for the switch, 130

- directive means for automatically operating the primary magnet to drive the switch into selective relation to a random said group, automatically applied means for causing the secondary magnet to drive the switch over the terminals of the selected group, means depending upon what group the switch is driven into said selective relation to for thereupon disabling the secondary magnet from thereafter operating, and means dependent upon operating the switch by the primary magnet to one or another of a plurality of predetermined levels before the first said operation for disabling the last said means.
22. In a telephone system, a switch, a plurality of groups of line terminals, primary and secondary driving magnets for the switch, directive means for automatically operating the primary magnet to drive the switch into selective relation to a random said group, automatically applied means for causing the secondary magnet to drive the switch over the terminals of the selected group, means depending upon what group the switch is driven into selective relation to for thereupon disabling the secondary magnet from thereafter operating, and means dependent upon operating the switch by the primary magnet to a predetermined group before the first said operation for disabling the last said means.
23. In a telephone system, a switch, a plurality of groups of line terminals, primary and secondary driving magnets and a release magnet for restoring the switch, directive means for automatically operating the primary magnet to drive the switch into selective relation to a random said group, automatically applied means for causing the secondary magnet to drive the switch over the terminals of the selected group, means depending upon what group the switch is driven into selective relation to for thereupon disabling the secondary magnet from thereafter operating, and means dependent upon operating the switch by the primary magnet to a random one of a plurality of predetermined groups of said line terminals to thereupon automatically operate the release magnet responsive to attaining the selected group to restore the switch before the first said operation for disabling the last said means.
24. In a telephone system, a switch, levels of trunk line terminals of two numerical orders accessible from the switch, means for operating the switch in correspondence with the numerical orders, respectively, to select a trunk line of a corresponding numerical order level, and means for thereafter barring the switch from seizing a trunk of a selected level of one said numerical orders responsive to the switch being selectively operated with respect to a level in accordance with the other numerical order.
25. In a telephone system, a switch, groups of trunk line terminals of two numerical orders accessible from the switch, means for operating the switch in correspondence with the numerical orders, respectively, to select a trunk line of a corresponding numerical order group, and means for thereafter barring the switch from seizing a trunk of a selected group of one said numerical orders responsive to the switch being selectively operated with respect to a group in accordance with the other numerical order.
26. In a telephone system, a switch, groups of trunk line terminals of two numerical orders accessible from the switch, means for operating the switch in correspondence with the numerical orders, respectively, to select a trunk line of a corresponding numerical order group, and means for barring the switch from seizing a trunk of a selected group of one said numerical orders and for applying a signal responsive to the switch being selectively operated with respect to a group in accordance with the other numerical order.
27. In a telephone system, a switch, a plurality of levels of trunk terminals, specific levels belonging to specific numerical orders, means for operating the switch into selective relation to a random one of the levels and in hunting relation thereover, means for operating the switch with specific correspondence with the numerical orders, and means for thereafter maintaining the levels of one numerical order barred to the hunting operation of the switch unless a level of the last said levels has been selected by a corresponding numerical order operation.
28. In a telephone system, a switch, a plurality of groups of trunk terminals, specific groups belonging to specific numerical orders, means for operating the switch into selective relation to a random one of the groups and in hunting relation thereover, means for operating the switch with specific correspondence with the numerical orders, and means for thereafter maintaining the groups of one numerical order barred to the hunting operation of the switch unless a group of the last said groups has been selected by a corresponding numerical order operation.
29. In a telephone system, a switch, a plurality of levels of trunk terminals, specific levels belonging to specific numerical orders, means for operating the switch in selective relation to random said levels and in automatically applied hunting relation thereover, means for operating the switch with selective relation to a said level in correspondence with one or another of said numerical orders at will, and means for thereafter maintaining the levels of one numerical order barred to a hunting operation of the switch unless the said level when selected has been selected by a corresponding numerical order operation.

30. In a telephone system, a switch, a plurality of groups of trunk terminals, specific groups belonging to specific numerical orders, means for operating the switch in selective relation to random said groups and in automatically applied hunting relation thereover, means for operating the switch with selective relation to a said group in correspondence with one or another of said numerical orders at will, and means for thereafter maintaining the groups of one numerical order barred to a hunting operation of the switch unless the said group when selected has been selected by a corresponding numerical order operation.

31. In a telephone system, a switch, a plurality of groups of trunk terminals, specific groups belonging to specific numerical orders, means for operating the switch in selective relation to random said groups and in automatically applied hunting relation thereover, means for operating the switch with selective relation to a said group in correspondence with one or another of said numerical orders at will, means for maintaining the groups of one numerical order barred to a hunting operation of the switch unless the said group when selected has been selected by a corresponding numerical order operation, and a signal device operated responsive to a level being selected by a non-corresponding numerical order operation.

32. In an automatic telephone system, a switch, groups of trunks of two numerical orders selectively accessible from the switch, means for alternatively operating the switch depending upon in which numerical order group it is desired to select, and automatically applied means for thereafter disabling the switch from thereafter selecting responsive to the switch being operated into selective relation to a group by an operation alternative to the group selected.

33. In an automatic telephone system, a switch, groups of trunks of a plurality of numerical orders selectively accessible from the switch, means for correspondingly operating the switch depending upon in which numerical order group it is desired to select, and automatically applied means for thereafter disabling the switch from thereafter selecting responsive to the switch being operated into selective relation to a group by an operation not corresponding to the group selected.

34. In an automatic telephone system, a switch, groups of trunks of a plurality of numerical orders selectively accessible from the switch, means for correspondingly operating the switch depending upon in which numerical order group it is desired to select, automatically applied means for disabling the switch from thereafter selecting responsive to the switch being operated into selective relation to a group by an operation not

corresponding to the group selected, and a signal device rendered operated responsive to the disablement of the switch.

35. In an automatic telephone system, a calling line, a switch, groups of trunks of a plurality of numerical orders selectively accessible from the switch, means for correspondingly operating the switch depending upon in which numerical order group it is desired to select, automatically applied means for disabling the switch from thereafter selecting responsive to the switch being operated into selective relation to a group by an operation not corresponding to the group selected, and means for applying an audible signal to the calling line responsive to the disablement.

36. In an automatic telephone system, a wiper switch, a vertical magnet, a normally disabled rotary magnet, a release magnet, levels of line terminals accessible from the wipers, means for operating the vertical magnet to set the wipers in selective relation to a level, means for operating the rotary magnet for driving the wipers over the selected level, means for operating the release magnet to restore the switch, means depending upon operating the wipers into selective relation to a random one of a predetermined plurality of levels and also means for operating the wipers into selective relation to a random one of a predetermined plurality of other levels to operate the release magnet to render the rotary magnet thereafter operative.

37. In an automatic telephone system, a switch, a primary magnet, a normally disabled secondary magnet, a release magnet, groups of line terminals accessible from the switch, means for operating the primary magnet to set the switch in selective relation to a group, means for operating the secondary magnet for driving the switch with relation to the individual terminals of a selected group, means for operating the release magnet for restoring the switch, means depending upon operating the switch into selective relation to a predetermined group and also means for operating the switch into selective relation to a predetermined other said group to operate the release magnet to render the secondary magnet thereafter operative.

38. In an automatic telephone system, a switch, a shaft of the switch, a driving and a restoring magnet for the shaft, a switch-operating contact set companion to the shaft, means on the shaft for operating the contacts by a movement of the shaft when driven, and means independently operated by the restoring magnet for preventing the contact set from operating responsive to the first said means when the shaft is restored.

39. In an automatic telephone system, a switch, a shaft of the switch, a driving and a restoring magnet for the shaft, a switch-operating contact set companion to the shaft,

means on the shaft for operating the contacts by a movement of the shaft when driven, and means for preventing the contact set from operating responsive to the first said means 5 when the shaft is restored.

40. In an automatic telephone system, a switch, a plurality of levels of line terminals accessible from the switch, directive control means to operate the switch into selective relation to random said levels responsive to a single operation of the directive means, means responsive to a predetermined single directive operation of the directive means to effect a selection of only certain levels and 10 by an automatically applied hunting operation an idle line of the selected level, means responsive to two predetermined directive operations of the directive means to effect a selection of only certain levels and by an 15 automatically applied hunting operation an idle line of the selected level, and automatically applied means for disabling the switch from thereafter selecting a line of a level of last said levels if the level selected has not 20 been selected by its said two predetermined directive operations.

41. In an automatic telephone system, a switch, a plurality of groups of line terminals accessible from the switch, directive control means to operate the switch into selective relation to random said groups responsive to a single operation of the directive means, means responsive to a predetermined single directive operation of the directive means 30 to offset a selection of only certain groups and by an automatically applied hunting operation an idle line of the selected group, means responsive to two predetermined directive operations of the directive means to effect a selection of only certain groups and by an automatically applied hunting operation an idle line of the selected group, and automatically applied means for disabling the switch from thereafter selecting a line of a group of last said groups if 35 the group selected has not been selected by its said two predetermined directive operations.

42. In an automatic telephone system, a switch, a plurality of levels of line terminals accessible from the switch, directive control means to operate the switch into selective relation to random said levels responsive to a single operation of the directive means, 50 means responsive to a predetermined single directive operation of the directive means to effect a selection of a certain level and by an automatically applied hunting operation an idle line of the selected level, means responsive to two predetermined directive operations of the directive means to effect a selection of a certain other level and by an automatically applied hunting operation an idle line of the selected level, and automatically 55 applied means for disabling the switch from

thereafter selecting a line of last said level if the level has not been selected by its said two predetermined directive operations.

43. In an automatic telephone system, a switch, a plurality of groups of line terminals 70 accessible from the switch, directive control means to operate the switch into selective relation to random said groups responsive to a single operation of the directive means, means responsive to a predetermined single directive operation of the directive means to effect a selection of a certain group and by an automatically applied hunting operation an idle line of the selected group, means responsive to two predetermined directive 75 operations of the directive means to effect a selection of a certain other group and by an automatically applied hunting operation an idle line of the selected group, and automatically applied means for disabling the 80 switch from thereafter selecting a line of last said group if the group has not been selected by its said two predetermined directive operations.

44. In an automatic telephone system, a calling line, a tone source, a selective switch, groups of lines accessible from the switch, automatic means for directly operating the switch into selective relation to a said group to extend the calling line into connection with an idle line of the selected group, automatically applied means responsive to the said selection of a group to cause the switch to selectively hunt for an idle line of the selected group, automatically applied means for applying the tone source to the calling line consequent to the selection of the group, and automatically applied means for thereafter disconnecting the tone source 90 consequent to the hunting operation ensuing. 95

45. In an automatic telephone system, a calling line, a tone source, a selective switch, levels of lines accessible from the switch, automatic means for directly operating the switch into selective relation to a said level to 100 extend the calling line into connection with an idle line of the selected level, automatically applied means responsive to the said selection of a level to cause the switch to selectively hunt for an idle line of the selected level, automatically applied means for applying the tone source to the calling line consequent to the selection of the level, and automatically applied means for thereafter disconnecting the tone source 105 consequent to the hunting operation ensuing.

46. In an automatic telephone system, a calling line, a tone source, a selective switch, groups of lines accessible from the switch, automatic means for directly operating 115 the switch in a primary movement to select a said group to extend the calling line into connection with an idle line of the selected group, automatically applied means responsive to the said primary selection to cause the switch 120

130

to selectively hunt for an idle line of the selected group, automatically applied means for applying the tone source to the calling line consequent to the selection of the group, 5 and automatically applied means for thereafter disconnecting the tone source consequent to the hunting operation ensuing.

47. In an automatic telephone system, a source of signaling current, a signaling device, a selective switch, groups of lines accessible from the switch, automatic means for directly operating the switch into selective relation to a said group, automatically applied means responsive to the selection of a 10 said group to cause the switch to selectively operate with specific relation to the selected group, automatically applied means for applying the signaling current to operate the signaling device consequent to the said selection of the group, and automatically applied means to disconnect the signaling current consequent to the operation of the first said automatically applied means.

48. In a telephone system, a called line, an 25 idle and alternative busy state of the called line, a calling line, a plurality of switches for linking a connection from the calling line to the called line, means for barring talking relation from the calling line to the connected 30 called line only when busy, and automatic means individual to one of said switches for applying and thereafter finally disconnecting a 35 momentary tone to the called line responsive to the connection thereto only when the called line is busy.

49. In a telephone system, a called line, an idle and alternative busy state of the called line, a calling line, a plurality of switches for linking a connection from the calling line to the 40 called line, means for barring talking relation from the calling line to the connected called line only when busy, and automatic means individual to one of said switches for applying and thereafter finally effacing a 45 momentary apprising signal on the called line responsive to the connection thereto only when the called line is busy.

50. In a telephone system, a calling and a 50 called line connected in talking relation, another calling line, a plurality of automatic switches for linking a connection from said another calling line to one of said connected lines, means for barring talking relation from said another calling line connected to one of 55 the other said lines due to said one line being busy because of the first said connected condition, automatic means individual to one of said switches for applying and finally disconnecting a 60 momentary tone to the one of said first connected lines said another calling line is connected to responsive to the connection being effected from said another calling line to one of said first connected lines, and means for effecting said connection to one of

said first connected lines if idle without applying tone thereto. 65

51. In a telephone system, a calling and a called line connected in talking relation, another calling line, a plurality of automatic switches for linking a connection from said another calling line to one of said connected lines, means for barring talking relation from said another calling line connected to one of the other said lines due to said one line being busy because of the first said connected condition, automatic means individual to one of said switches for applying and thereafter finally effacing a momentary apprising signal on the one of said first connected lines said another calling line is connected to responsive to the connection being effected from said another calling line to one of said first connected lines, and means for effecting said connection to one of said first connected lines if idle without applying said apprising signal. 70 75 80 85

52. In a telephone system, an automatic switch having a movable shaft, selective terminals of the switch carried by the shaft, fixed terminals cooperative with the said selective terminals, an operating magnet for moving said shaft and selective terminals from normal idle position into selective relation to desired said fixed terminals, a restoring magnet for returning the shaft to its said 90 normal position, a set of switch circuit control springs, means for operating said springs responsive to the operation of the restoring magnet before the shaft returns toward its normal position independent of the 95 movement of the shaft, and means for thereafter at will effacing said operated state of said control springs responsive to again moving said shaft from its normal position. 100

53. In a telephone system, an automatic 105 switch having a movable shaft, an operating magnet for moving the shaft from its normal idle position, a restoring magnet for returning the shaft to its said normal position, a set of switch circuit control springs, means for operating said springs responsive to the operation of said restoring magnet in effacing said moved state of said shaft independent of the movement of the shaft, and means for thereafter effacing said operated state of said 115 control springs responsive to again moving said shaft from its normal position. 120

54. An automatic switch having a movable shaft, an operating magnet for moving the shaft from normal idle position, a restoring 120 magnet for returning the shaft to its normal position, a set of switch circuit control springs, means for operating said springs responsive to the operation of said restoring magnet in returning said shaft to its said normal position, a dog for retaining said operated springs in operated position after said shaft is restored, and means operated by the 125

operating magnet at will to disengage said dog for causing the effacement of the operated state of said springs.

55. In a telephone system, a first selective switch, a set of movable terminals of the switch, a plurality of levels of fixed terminal sets the sets of the respective levels each cooperative in like manner with the respective terminals of the set of movable terminals, a 10 trunk line leading from each set of fixed terminals, a selective switch terminating each said trunk line, a calling line leading-in to said first selective switch, means on the calling line for directly operating said first 15 switch to move said movable terminals in a first plane into selective relation with a random one of said levels, means for then operating the said movable terminals in a second plane having an angular relation to said first 20 plane along the selected level into connection with a set of said fixed terminals specific to the selected level, and means for preventing the operation of the said movable terminals along a predetermined said level unless the 25 said movable terminals are first operated from normal into selective relation to the last said level and thereupon restored therefrom to normal and again operated into selective relation to said level.

56. In a multi-office telephone system, a calling line in a first one of said offices, a first selective switch terminating the calling line, a set of movable link wiper terminals of the switch, fixed trunk terminal sets in a plurality 30 of levels commonly accessible in like manner by said movable terminals, a group of trunks leading from each of certain of said levels to different said offices other than said first office, a selective switch terminating each last said 35 trunk, a group of trunks leading from each of other certain of said levels to said first office, a selective switch terminating each last said trunk, and means so that the total number of levels having said groups of trunks leading 40 therefrom is less numerically than the sum of the said offices of the system and the number of groups of trunks leading to said first office.

57. In a multi-office telephone system, a calling line in a first one of said offices, a first selective switch terminating the calling line, a set of movable link wiper terminals of the switch, fixed trunk terminal sets in a plurality 45 of levels commonly accessible in like manner by said movable terminals, a group of trunks leading from each of certain of said levels to different said offices other than said first office, a selective switch terminating each last said trunk, a group of trunks leading 50 from each of other certain of said levels to said first office, a selective switch terminating each last said trunk, and means so that the total number of levels having said groups of trunks leading therefrom may be less numerically 55 than the sum of the said offices of the

system and the number of groups of trunks leading to said first office.

58. In an automatic telephone system, a combined first and second selector switch, a directively operable primary magnet and an 70 automatically operable secondary magnet for controlling the operation of said switch, a single set of wipers for said switch, means for operating said primary magnet and said secondary magnet only thereafter in one instance by impulses corresponding to the first digit of a called number to extend a connection over all of said wipers of said set of wipers and in another instance for operating said primary magnet by the impulses corresponding to the first and second digits of the called number and only thereafter the secondary magnet to extend a connection over the identical wipers of said set of wipers as used in the first said instance. 85

59. In a telephone system, a leading-in line, a selector terminating the leading-in line, a group of lines accessible from the switch, a calling device on the leading-in line, a first, a second and a third relay of the switch, means 90 for at will operating the first and second relays by the calling device to start the selective operation of the switch to select the said group of lines, self-acting means in the switch for continuing the selective operation of the 95 switch with respect to the individual lines of said group, means operated by the third relay for stopping the said continued operation when a predetermined line of the group is selected, and relays involving only said first 100 and second relays operated by said calling device for at will stopping the continued operation of the switch before said predetermined line has been selected irrespective of said third relay and without effacing the operated 105 state of the switch.

60. In a telephone system, a calling line, a selector terminating the calling line, switch means for connecting to the calling line, relays of the selector, a tone source, a group of line terminals accessible from the selector, automatic control means operated at will only after the calling line is connected with by the switch means for causing the operation of the relays to set the selector into hunting relation to the line terminals and seize the first idle one encountered, and relay means comprising only said relays operated for applying the tone source to the calling line responsive to the control means being operated while the selector is hunting. 110

61. In a telephone system, a calling line, a selector terminating the calling line, switch means for connecting to the calling line, relays of the selector, a tone source, a group of line terminals accessible from the selector, automatic control means operated at will only after the calling line is connected with by the switch means for causing the operation of the relays to set the selector into hunting relation 125 to the line terminals and seize the first idle one encountered, and relay means comprising only said relays operated for applying the tone source to the calling line responsive to the control means being operated while the selector is hunting. 130

- tion to the line terminals and seize the first idle one encountered, and relay means comprising only said relays operated for applying the tone source to the calling line and for disabling the selector from seizing responsive to the control means being operated while the selector is hunting.
62. In an automatic telephone system, a first selective switch, called lines reached through said first selective switch, said lines each having a numerical position in the system, levels of trunks leading from said first selective switch to selective switch groups wherein each said group has a different numerical rank, means whereby the individual said levels corresponding to one said rank of selective switches have a designation numerically corresponding to the level position in the said first selective switch the respective selective switches are reached over, said numerical designation being the first digit of the numbers indicating the numerical position of the terminals of the respective said lines reached through said first selective switch and also the numerical designation of one rank of said selective switch groups used for extending connection in accordance with a said first digit, means whereby the individual levels corresponding to a different said rank of said selective switches have a designation common to its different level positions in said first selective switch, last said designation being the first digit of the said line numbers indicating the numerical position of the terminals of said lines called through said first selective switch and said different rank of selective switches, and means whereby the position of the individual said lines reached through the two groups of selective switches will have the same numerical rank and will be indicated by the same number of digits in the respective call numbers thereof.
63. In an automatic telephone system, a first selective switch, called lines reached through said first selective switch, said lines each having a numerical position in the system, levels of trunks leading from said first selective switch to selective switch groups wherein each said group has a different numerical rank, means whereby the individual said levels corresponding to one said rank of selective switches have a designation numerically corresponding to the level position in the said first selective switch the respective selective switches are reached over, said numerical designation being the first digit of the numbers indicating the numerical position of the terminals of the respective said lines reached through said first selective switch and also the numerical designation of one rank of said selective switch groups used in extending connection in accordance with a said first digit, means whereby the individual levels corresponding to a different said rank of said selective switches have a designa-

tion common to its different level positions in said first selective switch, last said designation being the first digit of the said line numbers indicating the numerical position of the terminals of said lines called through said first selective switch and said different rank of selective switches, and wherein the second digit of the call number of each said line reached through said different rank of selective switches will refer to a numerically corresponding level of the said first selective switch, and means whereby the position of the individual said lines reached through the two groups of selective switches will have the same numerical rank and will be indicated by the same number of digits in the respective call numbers thereof.

64. In an automatic telephone system, a calling line, a first selective switch terminating the calling line, a calling device on the calling line, a set of wipers of said switch, levels of bank terminal sets in levels of said switch, each said set of bank terminals cooperative with all the wipers of said set in like manner, second selective switches, called lines, the respective said second switches connected direct to levels of said first switch, means for sending a single series of impulses from the calling device to operate said first switch to connect with one of said second switches, means for operating said first switch only responsive to two series of impulses from the calling device to connect said first switch with certain of said second switches, means whereby the first series sent in effecting last said connections by two series will always have the same number of impulses in the first one of said two series, third selective switches for extending connection from said second selective switches to the one of said called lines called, and means whereby the same number of series will be required to effect connection from the calling line to a random said called line by said first selective switches and certain of other said switches wherein the number of switches operated to link the connection from the calling line to the called line will not necessarily be the same for all connections from said calling line to the line called of said called lines.

65. In a telephone system having a uniform numbering system in which all of the subscribers have the same number of digits in their telephone numbers, means including a first selector and a plurality of serially related directly controlled automatic switches for connecting a calling and a called subscriber's line, said first selector having a single set of wipers, a vertical magnet, a rotary magnet, a release magnet and a plurality of relays individual thereto for operating said selector, said first selector and a different and lesser number of similar said switches for connecting the said calling line with another called line, means in the first selector used when

- calling the said another called line for canceling one of the digits in the number thereof, and means whereby the same number of said relays are operated for all said connections 5 effected through said first selector.
66. In a telephone system having a uniform numbering system in which all of the subscribers have the same number of digits in their telephone numbers, means including a 10 first selector and a plurality of serially related directly controlled automatic switches for connecting a calling and a called subscriber's line, said first selector having a single set of wipers, electro-magnetic means for variously 15 positioning said wipers, a plurality of relays individual to said first selector, said first selector and a different and lesser number of similar said switches for connecting the said calling line with another called line, means in 20 the first selector used when calling the said another called line for canceling one of the digits in the number thereof, and means whereby the same number of said relays are operated for all said connections effected 25 through said first selector.
67. In a telephone system having a uniform numbering system in which all of the subscribers have the same number of digits in their telephone numbers, means including a 30 first selector and a plurality of serially related directly controlled automatic switches for connecting a calling and a called subscriber's line, said first selector having a single set of wipers, electro-magnetic means 35 for variously positioning said wipers, a plurality of relays not exceeding five individual to said first selector, said first selector and a different and lesser number of similar said switches for connecting the said calling line 40 with another called line, means in the first selector used when calling the said another called line for canceling one of the digits in the number thereof, and means which avoids using more said relays in last said connection 45 than in first said connection.
68. In a telephone system having a uniform numbering system in which all of the subscribers have the same number of digits in their telephone numbers, means including a 50 first selector for directly connecting a calling and a called subscriber's line, said first selector having a single set of wipers and a plurality of bank levels accessible from said wipers, means whereby the first digit of certain telephone numbers will determine what 55
- particular level of the first selector will be used in completing the connection to the line indexed by the number called, means whereby the first digit of other certain telephone numbers will only determine a plurality of said 60 levels an unknown one of which will be used in completing the connection to the line indexed by the number called, and means whereby the second digit of said other certain telephone numbers will determine which particular one of the levels of said plurality last determined will be used in completing the connection to the line indexed by the number called. 65
69. In a telephone system having a uniform 70 numbering system in which all of the subscribers have the same number of digits in their telephone numbers, means including a first selector and a plurality of serially related directly controlled automatic switches for 75 connecting a calling and a called subscriber's line, said first selector having a single set of wipers and a plurality of bank trunk levels accessible from said wipers, means whereby the first digit of certain telephone numbers 80 will determine what particular level of the first selector will contain the trunk to be used in completing the connection to the line indexed by the number called, means whereby the first digit of other certain telephone numbers 85 will only determine a plurality of said levels an unknown one of which will contain the trunk to be used in completing the connection to the line indexed by the number called, and means whereby the second digit of said other certain telephone numbers will determine which particular one of the levels of said plurality last determined will contain the trunk to be used in completing the connection to the line indexed by the number called. 90
70. In a telephone system, a called line, an idle and alternative busy state of the called line, a calling line, a plurality of switches for linking a connection from the calling line to the called line, means for barring talking relation from the calling line to the connected called line only when busy, and automatic means individual to one of said switches for applying and thereafter finally disconnecting a momentary tone to the called line responsive 95 to the connection thereto when the called line is busy. 100
- In witness whereof, I hereunto subscribe my name this nineteenth day of August, 1924.
- HERBERT M. FRIENDLY.
